(57) **CLAIM**

I claim the ornamental design for a reinforcing bar protection cap, as shown and described.

DESCRIPTION

FIG. 1 is a top perspective view of a reinforcing bar protection cap showing my new design;
FIG. 2 is a bottom perspective view thereof;
FIG. 3 is an enlarged scale bottom plan view;
FIG. 4 is an enlarged scale top plan view;
FIG. 5 is an enlarged scale left side elevational view with the right side elevational view being a mirror image; and,
FIG. 6 is an enlarged scale front elevational view with the rear elevational view being a mirror image.
